Specification for Design. Patented Apr. 26, 1921.

Application filed January 17, 1921. Serial No. 438,008. Term of patent 3½ years.

To all whom it may concern:

Be it known that I, SISSAK K. OUZOUN-BOGHSSIAN, a subject of the Sultan of Turkey, having declared my intention of becoming a citizen of the United States, residing at the city of Washington, District of Columbia, have invented a new, original, and ornamental Design for Grilles for Talking-Machines, of which the following is a specification, reference being had to the accompanying drawing, forming part hereof.

The figure is a plan view of a grille for talking machines, showing my new design.

I claim:

The ornamental design for a grille for talking-machines, as shown.

In testimony whereof I affix my signature.

SISSAK K. OUZOUN-BOGHSSIAN.
